Attest

UNITED STATES PATENT OFFICE.

WILLIAM S. HAMM, OF HUBBARD WOODS, ILLINOIS, ASSIGNOR TO THE ADAMS & WESTLAKE CO., A CORPORATION OF ILLINOIS.

DOOR.

Application filed September 4, 1920. Serial No. 408,285.

To all whom it may concern:

Be it known that I, WILLIAM S. HAMM, a citizen of the United States, and resident of Hubbard Woods, county of Cook, and 5 State of Illinois, have invented certain new and useful Improvements in Doors, of which the following is a specification, and which are illustrated in the accompanying drawings, forming a part thereof.

10 The invention relates particularly to sheet metal doors, though as to some of its features it might be applied to doors made of other material without departing from its scope. The object of the invention is to provide 15 means for supporting the case of a mortise lock or latch and it consists of a structure such as hereinafter described and in which two preferred forms of embodiment are illustrated in the accompanying drawings in 20 which;—

Fig. 1 is a detail edge view of the door;
Fig. 2 is a sectional detail on the line 2—2

of Fig. 1;

Fig. 3 is a sectional detail on the line 25 3—3 of Fig. 2;

Fig. 4 is a view similar to Fig. 1, showing the modified form of construction;

Fig. 5 is a sectional detail on the line 5—5 of Fig. 4, and

30 Fig. 6 is a sectional detail on the line 6—6 of Fig. 5, the latching element being omitted.

In sheet metal doors, particularly such as are now coming into common use in railway cars, it is desirable to use a latch of the mortise type and it is important that such latch shall be applied with a minimum cutting away or aperturing of the edge and side walls of the door. It is further desirable to provide means for securing the latch 35 casing without depending upon screws for that purpose and also without throwing upon the latch controlling spindle the duty of sustaining the force of jars incident to service. These various objects are secured 40 by the present invention.

The side walls of a sheet metal door are shown in the drawings at 10, 11, and its edge wall at 12. These various walls may be secured together in any preferred manner 45 and, as this present invention is not concerned with this feature of the door, such securing means are not illustrated.

The latching dog 13 is shown as of the pivoted type and as being carried by a cas-

ing 14 which is inserted through an aperture in the edge of the door proportioned and configured to insure a snug fit of the end plate of the casing therein. The usual spindle for controlling the latch dog is shown at 15 and to its ends are applied suitable handles 16, 17, of any preferred form. At 18, 19, there are shown a pair of escutcheon plates which are fitted against the side walls of the door and are preferably secured together by means of screws 20 entered into or through a pair of abutting posts 21, 22, formed respectively upon the two escutcheon plates and projecting into suitable apertures in the door walls.

In the construction shown in Figs. 1, 2 and 3 a sheet metal strap 23 formed into a loop, which will snugly receive the latch casing, is secured within the chamber of the door by means of screws or rivets, as 24, setting through the edge wall of the door 70 and outwardly turned ends 25, 26, of the strap. The length of the loop 23 is such that the inner end of the casing makes contact with it when the casing is properly positioned and its width is such that the side 75 margins of the casing bear against each of its side members whereby the casing is supported and is prevented from displacement either vertically or horizontally, the spindle 15 holding it against outward movement. The latch casing is preferably provided at its inner end with one or more 80 lugs, as 27, adapted to bear against the inner face of one of the side walls of the door.

In the construction illustrated in Figs. 4, 5, and 6, a shelf 28 is provided for supporting the latch casing, a stop 29 for limiting its inward movement, and a stop 30 for preventing its upward movement, are provided 95 by cutting one of the side walls of the door and then bending in the material on the planes to be occupied respectively by the bottom, the inner end and the top margin of the latch casing.

While I have shown two practical and so far as I am at present advised, the most desirable forms for the invention, it may be variously embodied, the most essential feature being the provision of the shelf for 105 supporting the latch casing.

I claim as my invention:

1. A hollow door adapted to receive a

mortise-latch casing, and having a shelf within its chamber for supporting such casing.

2. A hollow door adapted to receive a mortise-latch casing, and being provided with a shelf upon which the casing is supported and a stop for limiting the inward movement of such casing.

3. A hollow door adapted to receive a mortise-latch casing, and being provided with a shelf upon which the casing is supported and stops for engagement by the inner end and top margin of such casing.

4. In a door having an opening for receiving the casing of a mortise-latch and a metal loop secured with such opening for

supporting such casing and limiting its inward and upward movements.

5. A chambered sheet metal door having an opening for receiving a latch casing, and a sheet metal loop into which the casing will fit, the ends of the loop being secured to the side edge of the door.

6. A hollow metal door having side and edge walls, the edge wall being apertured to receive a mortise-latch casing, and a metal loop having its ends secured to the edge wall of the door and its body portion enclosing the aperture and being of such size as to receive the latch casing.

WILLIAM S. HAMM.
